UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

BUTTONHOLE-SEWING MACHINE.

1,418,223.

Specification of Letters Patent. Patented May 30, 1922.

Application filed August 12, 1920. Serial No. 403,072.

To all whom it may concern:

Be it known that I, EDWARD B. ALLEN, a citizen of the United States, residing at Newtown, in the county of Fairfield and State of Connecticut, have invented certain new and useful Improvements in Button-hole-Sewing Machines, of which the following is a specification, reference being had therein to the accompanying drawings.

10 This invention relates to sewing machines, more particularly of the buttonhole sewing type such as disclosed in my Patents No. 767,539 of August 16, 1904, No. 806,231 of December 5, 1905 and No. 885,310 of April 15 21, 1908, and has for an object to provide a smooth running and durable machine for sewing what is known as a "slant-barred" buttonhole, i. e., a buttonhole having barring stitches arranged across one end of the buttonhole-slit at an acute angle to the latter. A buttonhole of this type has been proposed for the front closure of the usual starched collar and is designed to prevent the tearing out of the end of the buttonhole and to assist in preventing the formation of a gap 25 at the front of the collar between the ends of the fold which connects the neck and outer bands.

On account of the unusual length and 30 inclined position of the so-called "slant-bar," no machine has been devised up to the present time, so far as I am aware, for sewing a buttonhole of this character.

With the purpose in view of avoiding 35 harsh motions, the invention has for a further object to provide an improved needle-jogging mechanism particularly adapted for cooperation with the work-holder shifting mechanism during the slant-barring operation.

Still further, the invention has for an 40 object to provide for the release of the sewing thread tension during the slant-barring operation, at which time an abrupt and unusual demand is made upon the supply of 45 sewing thread.

To the attainment of the ends in view the invention is preferably embodied in a

machine of the general type disclosed in my said patents. In the present machine, the 50 general form of the frame and the construction of the stitch-forming mechanism, work-holder, stop-motion, buttonhole and thread-cutting devices are substantially in accordance with the usual practice represented by 55 said patents and the well known Singer Class 71 machine.

Material and important modifications have been made, however, in the mechanism for jogging the needle and for shifting the 60 work-holder, in order to sew the inclined barring stitches in a feasible and practical manner. To this end, in the preferred embodiment of the invention, a vertical cam-shaft is arranged in front of the bracket-arm standard. This shaft is preferably 65 geared to the needle-actuating shaft and preferably makes not more than one revolution for a buttonhole-producing cycle. At its upper end, this shaft carries a needle-jogging cam having easy cam throws, certain of which are of increased amplitude to 70 increase the jogging motion of the needle during the barring operations. This cam also carries one or more tension-releasing 75 cam-plates which come into action during the barring operations.

The cam-shaft carries at its lower end a feed-wheel having a cam-groove for shifting the work-holder laterally of the button-hole-slit. For shifting the work-holder longitudinally of the buttonhole-slit the feed-wheel is provided with two cam-grooves which are entered by separate 80 cam-followers carried by a linkage so contrived as to transmit to the work-holder the resultant of the individual throws produced by the cam-grooves. By virtue of this mechanism jogging movements of unusually 85 large amplitude may be imparted to the work-holder without recourse to abnormally large cams or cams having harsh or abrupt throws. The mechanism is thus particularly suited for the purpose of relatively moving 90 the stitch-forming mechanism and work-holder during the slant-barring operation. 95

The invention further comprises certain details of construction and combinations of parts hereinafter described and particularly pointed out in the appended claims.

- 5 In the accompanying drawings Fig. 1 is a side elevation of the machine embodying the invention. Figure 2 is a top plan view of the machine showing the casing for the needle-jogging cam in horizontal section. 10 Fig. 3 is a top plan view of the work-holder and feed-wheel. Fig. 4 is a bottom plan view of the feed-wheel and connections for shifting the work-holder. Figs. 5 and 6 are respectively, sections on the line 5—5 and 15 6—6, Fig. 3. Fig. 7 is a section on the line 7—7, Fig. 1, showing the feed-cam and work-holder shifting connections in elevation as viewed from the rear end of the machine. Fig. 8 is a detail top plan view of the 20 bracket-arm construction. Fig. 9 is a section on the line 9—9, Fig. 8. Fig. 10 is a diagrammatic top plan view showing the positions of consecutive needle-punctures during a buttonhole-producing cycle. Fig. 25 11 is an enlarged top plan view of a stitched buttonhole produced by the machine, and Fig. 12 is a diagrammatic view illustrating the lateral throws of the needle and work-holder in sewing a buttonhole.
- 30 In the preferred embodiment of the invention, as illustrated, the machine is constructed with a frame comprising a bed 1, standard 2, bracket-arm 3 and head 4. The reciprocating needle-bar 5 carrying the eye-pointed needle 6 is journaled in the usual swinging gate 7 mounted on pivotal centers 8, 9 and deriving its vibratory movement from a needle-jogging cam 10 fixed to the vertical cam-shaft 11 which is disposed 35 in front of the standard 2 and extends from the bracket-arm 3 to a point below the bed 1. The needle-jogging cam 10 has in its under face a groove 12 which is entered by a follower 13 on one arm of a lever 14 fulcrumed at 15 to the bracket-arm 3. The other arm of the lever 14 is formed with a segmental slot 16 affording an adjustable connection at 17 with one end of a link 18 the opposite end of which is connected at 19 40 to the needle-gate 7. The needle-jogging cam 10 is disposed above the bracket-arm 3 and is normally mounted within the casing 20.
- 45 The needle-bar 5 receives its reciprocatory motion through the usual pitman connection 21 with a crank 22 at the forward end of the main or needle-driving shaft 23 which is journaled within and longitudinally of the bracket-arm 3 and at its rearward end carries the usual tight and loose belt-pulleys 24 and 25, respectively, forming a part of the usual stop-motion device which also includes the pivoted stop-motion lever 26 carrying the belt-shipper 27, all as 50 more fully described in my said patents.

The vertical cam-shaft 11 receives step-by-step rotary motion from the needle-actuating shaft 23 which carries a bevel pinion 28 meshing with the gear 29 journaled on the pin 30 which is sustained by a cross-member 31 within the bracket-arm. The hub 32 of the gear 29 is enlarged at its upper end to form a disk 33 into the recessed upper face of which is let a diametrically extending plate 34, Figs. 2 and 9, carrying 75 a pair of diametrically opposed pins 35 adapted to mesh with the star-wheel 36.

The star-wheel 36 is screwed to the hub 37 of the pinion 38 which is journaled on the stationary pin 39 and meshes with the gear 40 fixed to the cam-shaft 11. It will be readily understood that the pin and star-wheel drive operates to impart a slow step-by-step rotary motion to the cam-shaft 11; the shaft 11 pausing while the needle 6 is in 85 the work. In the present instance, the ratio of gearing is such that the shaft 11 makes one complete revolution per buttonhole producing cycle.

The work-holder is of usual form and 90 comprises a longitudinal slide-plate 41 carrying a pivotally mounted upper clamping arm 42 to the forward end of which is pivoted at 43 the yoke 44 pivotally sustaining the clamping foot 45. The longitudinal 95 slide-plate is mounted in suitable guideways upon the usual transverse slide-plate 46 which is shifted crosswise of the bed 1 by means of the lever 47 pivoted at 48 beneath the bed 1 and carrying a follower-roll 49 entering a cam-groove 50 in the upper face of the feed-wheel 51 fixed to the lower end of the cam-shaft 11.

The longitudinal slide-plate 41 is shifted relative to the transverse slide-plate 46 by 105 the following mechanism. Mounted in the lug 52 depending from the bed 1 is a horizontal bearing sleeve 53 in which is fitted a slide-rod 54 to the forward end of which is fixed a bracket-piece comprising an upwardly extending curved arm 55 and a laterally extending arm 56. The arm 55 carries at its free end the vertical pin 57 which enters a block 58 fitted to slide along the guide-slot 59, Fig. 3, in the plate 60 fixed by screws 110 61 to the forward end of the bed 1. A portion of the block 58 projects above the plate 60 and enters a transverse slot 62 in the horizontal slide-plate 41.

Longitudinal motion is imparted to the 115 longitudinal slide-plate by means of a special cam-actuated linkage. Pivoted at 63 beneath the bed 1 is a lever 64 having a follower-roll 65 which enters a cam-groove 66 in the under face of the feed-wheel 51. 125 The lever 64 is connected at 67 to one end of a link 68, the opposite end of which is connected at 69 to one end of a lever 70 having a floating fulcrum 71 intermediate its ends. At its other end 72 the lever 70 is 130

connected by means of a link 73 to the lateral arm 56 of the bracket-piece 55, 56. The floating fulcrum 71 is sustained at one end of a rock-arm 74 pivotally mounted at 75 beneath the bed 1. At its free end the arm 74 carries a roll 76 which enters a second cam-groove 77 in the under face of the feed-wheel 51. The cam-groove 66 is concentric with the shaft 11 throughout the major portion 10 of its extent but has a stepped or active portion 78 which comes into action on the follower-roll 65 during the sewing of the slant bar. The cam-groove 77 is eccentric to the shaft 11 and acts to impart a slow progressive backward and forward movement to the work-holder while the sewing proceeds along one side and back along the other side of the buttonhole-slit. The cam-groove 77 is also formed with a stepped portion 79 which comes into action upon the follower 76 during the sewing of the slant bar at the end of the first side stitching operation. The stepped portions 78 and 79 of the cam-grooves 66 and 77, respectively, are so designed as to act simultaneously and in the same direction upon the work-holder. Thus, the motion produced by one cam is augmented by the motion produced by the other cam and the resultant increased motion is imparted to the work-holder.

The tension device 83 for the needle-thread is mounted on the casing 20 and is constructed with the usual release pin 84 which, in the present instance, rests upon the upper face of the cam-disk 10 to which is secured the tension-releasing cam-plates 85 and 86. These plates ride under and lift the tension-releasing pin 84 during the barring operations, thus relieving the needle-thread 40 of the drag produced by the tension device 83 at the time when an abnormal demand is made upon the supply of needle-thread.

During the side stitching operations, the tension on the needle-thread *e*, Fig. 11, is such as to cause the latter to lay substantially straight along the buttonhole slit *e*; the lower thread-loops *f* being drawn through to the upper side of the work. During the barring operations, however, the tension on 50 the needle-thread is relieved and is not sufficient to draw the lower thread loops to the upper side of the work.

Referring to Figs. 10, 11 and 12, the needle makes the first puncture at the point 55 1', Fig. 10, and, as the work-holder is moved step-by-step lengthwise of the machine-bed by the cam 77, the cam 12 operates to vibrate the needle so that the needle will make slit and depth stitches alternately. At the completion of stitch 43' the work-holder is jogged laterally in the same direction as the needle but to a lesser extent, as shown in 60 Fig. 12, whereby the stitch 44' is placed at a distance from the line of overedge stitches 65 equal to the difference between the throws

of the needle and work-holder. At the completion of stitch 44' the work-holder is shifted to central position and the needle is given an increased amplitude of vibration so that stitch 45' will be laid somewhat outside of the row of depth stitches. At this point the first side stitching operation is completed and the stepped portions 78 and 79 of the feed-cams act to vibrate the work-holder longitudinally, the amplitude of such vibratory motion being substantially equal to the distance between stitches 35' and 45', or a distance of ten stitches. At the same time, the stepped portion 80 of the cam-groove 50 acts through the lever 47 to impart lateral vibratory components of motion to the work-holder, in time with the lateral vibrations of the needle but opposite in direction as shown in Fig. 12, so that the stitches 46' to 54' will be piled upon one another across one end of the buttonhole-slit to form the slant bar *a*, one end *b* of which is anchored in the material at a considerable distance from the buttonhole-slit *c*. At the completion of stitch 54', which is the last of 85 the slant barring stitches, the opposite throws of the needle and work-holder are reduced in amplitude so that stitch 55' will be laid substantially at the center line of the buttonhole. At the completion of stitch 55' 95 the work-clamp is jogged in the same direction as the needle but to a lesser extent, so that the stitch 56' will not be laid beyond the slant bar *a* but will be set inwardly from the line of depth stitches 58'-94', a distance equal to the difference between the lateral throws of the needle and work-holder. For the production of stitch 57' the needle and work-holder are shifted to same 100 respective positions which they occupy in 105 the production of stitch 55'. During the second side stitching operation the work-holder remains in a laterally fixed position at one side of its central position, while the jogging needle alternately lays the slit and depth stitches. At the end of the second side-stitching operation, the work-holder is shifted to central position and the throw of the needle increased to sew the usual square bar *d* across the end of the button-hole-slit. 110 The needle-vibrating cam is not uniformly stepped throughout its extent but is designed with stepped portions 81 and 82 of increased amplitude to increase the amplitude of vibration of the needle during the 115 barring operations.

The invention is not to be understood as limited to the form and arrangement of parts shown and described as, in a sense, it is generic in character; the present machine 125 being the first to sew a slant-barred button-hole.

Having thus set forth the nature of the invention, what I claim herein is:

1. A buttonhole sewing machine having,

in combination, stitch-forming mechanism, a work-holder, and feeding and barring mechanism for relatively moving the stitch-forming mechanism and work-holder to sew 5 around and bar one end of a buttonhole, said feeding and barring mechanism including means for relatively moving the stitch-forming mechanism and work-holder to and fro repeatedly in an inclined direction across one 10 end of the buttonhole during the barring operation.

2. A buttonhole sewing machine having, in combination, stitch-forming mechanism including a laterally jogging needle, a work-holder, feeding and barring mechanism for moving the work-holder to sew around and bar one end of a buttonhole, said feeding 15 and barring mechanism including means for moving the work-holder to and fro repeatedly lengthwise of the buttonhole slit in timed relation with the lateral jogging movements of the needle during the barring operation, thereby forming a slant barred buttonhole.

25 3. A buttonhole sewing machine having, in combination, a buttonhole slit cutter, a needle mounted for reciprocatory and lateral jogging movements, a needle-jogging cam making not more than one revolution for 30 each buttonhole-producing cycle and connections for jogging the needle laterally of the buttonhole slit, a work-holder, and feeding mechanism including a feed-cam making not more than one revolution for each buttonhole-producing cycle and connections for 35 moving the work-holder lengthwise of the buttonhole-slit.

4. A buttonhole sewing machine having, in combination, a buttonhole slit cutter, a 40 needle mounted for reciprocatory and lateral jogging movements, a needle-jogging cam making not more than one revolution for each buttonhole-producing cycle and connections for jogging the needle laterally of the buttonhole-slit, a work-holder, feeding mechanism including a feed-cam making not 45 more than one revolution for each buttonhole-producing cycle and connections for moving the work-holder lengthwise of the buttonhole-slit, a driving shaft connected to 50 said cams, and means for imparting step-by-step rotary motion to said shaft.

5. In a buttonhole sewing machine, a needle jogging cam, a feed-cam, a shaft carrying said cams, and means for imparting intermittent rotary motion to said shaft.

6. A buttonhole sewing machine having, in combination, a buttonhole slit cutter, a needle mounted for reciprocatory and lateral 60 jogging movements, a needle-jogging cam making not more than one revolution for each buttonhole-producing cycle and connections for jogging the needle laterally of the buttonhole-slit, a work-holder, feeding mechanism including a feed-cam making not 65

more than one revolution for each buttonhole-producing cycle and connections for moving the work-holder lengthwise of the buttonhole-slit, a sewing shaft, a cam-shaft connected to said cams, and a pin and star-wheel timing connection between said shafts. 70

7. A buttonhole sewing machine having, in combination, a frame including a base, a standard and an overhanging bracket-arm, a needle, a needle-driving shaft and connections for reciprocating said needle, a vertical cam-shaft extending between the base and bracket-arm, a needle-jogging cam carried at the upper end of said cam-shaft and connections for imparting lateral jogging movements to the needle, a work-holder, a feed-cam carried at the lower end of said cam-shaft and connections for moving the work-holder, and means connected with the needle-driving shaft for driving said cam-shaft. 75

8. A buttonhole sewing machine having, in combination, a frame including a base, a standard and an overhanging bracket-arm, a needle, a needle-driving shaft and connections for reciprocating said needle, a vertical cam-shaft extending between the base and bracket-arm, a needle-jogging cam carried at the upper end of said cam-shaft and connections for imparting lateral jogging movements to the needle, a work-holder, a feed-cam carried at the lower end of said cam-shaft and connections for moving the work-holder, and means connected with the needle-driving shaft for driving said cam-shaft. 80

95

9. A buttonhole sewing and barring machine having, in combination, a buttonhole slit cutter, a needle mounted for reciprocatory and lateral jogging movements, a work-holder, a sewing shaft and connections for reciprocating said needle, a cam-shaft making not more than one revolution for each buttonhole-producing cycle, a needle-jogging cam on said cam-shaft and connections for jogging said needle laterally of the buttonhole-slit, and a feed-cam on said cam-shaft and connections for moving the work-holder to place the stitches around the buttonhole-slit, certain throws of the needle-jogging cam being increased to increase the amplitude of the jogging movements of the needle in barring. 100

10. A buttonhole sewing and barring machine having, in combination, a buttonhole-slit cutter, a needle mounted for reciprocatory and lateral jogging movements, a work-holder, a sewing shaft and connections for reciprocating said needle, a cam-shaft making not more than one revolution for each buttonhole-producing cycle, a needle-jogging cam on said cam-shaft and connections for jogging said needle laterally of the buttonhole-slit, a feed-cam on said cam-shaft and connections for moving the work-holder to place the stitches around the buttonhole- 115

100

slit, certain throws of the needle-jogging cam being increased to increase the amplitude of the jogging movements of the needle in barring, and the feed-cam operating to 5 impart a jogging movement to the work-holder lengthwise of the buttonhole-slit in slant barring one end of the buttonhole.

11. In a machine adapted to sew a group of stitches and then come to rest, in combination, a needle, a needle-jogging cam making not more than one revolution for 10 each sewing cycle, a needle thread tension, and means actuated by said cam for releasing the tension during one or more periods of the sewing cycle.

12. In a machine adapted to sew a group of stitches and then come to rest, in combination, a needle, a needle jogging cam making not more than one revolution for 20 each sewing cycle and adapted to increase the amplitude of the jogging movements imparted to the needle during a period of the sewing cycle, a needle thread tension, and means actuated by said cam for releasing 25 the tension during the period of increased amplitude of needle jogging movements.

13. A buttonhole sewing machine having, in combination, a buttonhole slit cutter, a needle mounted for reciprocatory and lateral jogging movements, a work-holder, a sewing shaft and connections for reciprocating the needle, a needle jogging cam making not 30 more than one revolution for each buttonhole producing cycle and connections for jogging the needle transversely of the buttonhole slit, a feed-cam and connections for moving the work-holder to place the stitches around the buttonhole slit and to place barring 35 stitches at at least one end of the buttonhole slit, a tension device for the needle-thread, and means including a cam-element carried by the needle jogging cam for releasing the tension when barring.

45. 14. In a sewing machine, in combination, a driven element, a plurality of driving and corresponding vibratory follower elements, and means connecting said follower elements in series and to said driven element.

50. 15. In a sewing machine, in combination, a driven element, a primary lever, an actuator for vibrating said lever, a secondary lever having a floating fulcrum, a second actuator for vibrating said floating fulcrum 55 in synchronism with the vibrations of the primary lever, a connection between said levers, and a connection between the secondary lever and the driven element.

16. A sewing machine having, in combination, 60 stitch-forming mechanism including a reciprocating needle, a work-holder, and means for producing relative jogging movements between the needle and work-holder, said means including a driven element, a plurality of driving elements, and connec-

tions for transmitting to the driven element the resultant of the individual throws of the respective driving elements.

17. A sewing machine having, in combination, 70 a stitch-forming mechanism including a reciprocating needle, a work-holder, and means for producing relative jogging movements between the needle and work-holder, said means including a driven element, a plurality of driving elements, a plurality of 75 follower elements, and means for connecting said follower elements in series and to said driven element.

18. A sewing machine having, in combination, 80 a stitch-forming mechanism, a work-holder, and means for producing relative jogging movements between said stitch-forming mechanism and work-holder, said means comprising a driven element, a plurality of driving cams, a plurality of cam-followers, one for each of the respective cams, and a linkage connecting said driven element with said cam-followers and operating to transmit the resultant of the individual movements of said cam-followers to 90 said driven element.

19. In a sewing machine, in combination, 95 stitch-forming mechanism, a work-holder, and a plurality of cams and corresponding cam-followers connected to said work-holder, one of said cams operating to augment the movement of the work-holder produced by the other cam-follower.

20. In a sewing machine having, in combination, 100 a frame, stitch-forming mechanism, a work-holder, and means for imparting stitch-positioning movements to the work-holder, said means including a plurality of cams, a lever fulcrumed on the frame and actuated by one of said cams, a second lever 105 having a floating fulcrum the position of which is governed by another of said cams, a link connection between said levers, and means for connecting said second lever with the work-holder.

21. In a buttonhole sewing machine, a 110 buttonhole slit cutter, a work-holder, and means for moving the work-holder lengthwise of the buttonhole-slit comprising, a horizontally disposed feed-wheel, a rod 115 slideable lengthwise of the buttonhole-slit and disposed below said feed-wheel, an operative connection between said feed-wheel and slide-rod, and an upright arm carried by said slide-rod for transmitting motion to the 120 work-holder.

22. A buttonhole sewing machine having, 125 a frame including a base, standard, and overhanging bracket-arm, a sewing shaft extending lengthwise of the bracket-arm, a stitch-forming mechanism including a reciprocating needle connected to said sewing shaft, a work-holder, a feed-shaft extending transversely of the sewing shaft between the bracket-arm and base, a feed-wheel mounted 130

on the feed-shaft, and means carried by the bracket-arm and connected to the sewing shaft for transmitting motion to the feed-shaft from the sewing shaft during the 5 sewing.

23. In a machine adapted to sew a group of stitches and then come to rest, in combination, a reciprocating needle, a cam and

connections for jogging said needle laterally of its direction of reciprocation, a needle-thread tension, and actuating means on said cam and connections for releasing said tension. 10

In testimony whereof, I have signed my name to this specification.

EDWARD B. ALLEN.
